LABEL FOR FLOOR COVERINGS

Original application filed March 28, 1932, Serial No. 601,548. Divided and this application filed June 8, 1932. Serial No. 616,052.

This invention relates to a combined floor covering, such for instance as carpets and rugs, and an identifying marker or label and is a division of application Ser. No. 601,548, filed March 28, 1932.

It has been the usual practice heretofore to display upon carpets and rugs which are offered for sale sufficient information to identify the kind of fabric, its maker and possibly other information, and the practice has been to mark or display this information upon the back of the carpet or rug.

This practice is open to the objection that it requires that the floor covering be turned or folded back to display the marking upon its lower face, and when a number of floor coverings are arranged in a stack or pile the marking upon the back of one cannot be examined until the superposed rugs or carpets are themselves shifted.

Where the carpet or rug is provided with a pile surface formed of projecting yarns secured to the backing fabric, it is desirable that the label shall be so applied to the carpet or rug as that it will not cause any appreciable depression of the pile forming area, and in accordance with the present invention the label has end portions which are secured to the floor covering in such manner that the data bearing portion of the label shall extend over and above a part of the pile area without depressing it.

In accordance with the present invention the ends of the label are secured to the floor covering at separated points, one of which may be the end portion of the carpet or rug and the other a side portion thereof, so that the portion of the label extending between the ends shall be extended above and overlie a part of the pile surface.

The invention and novel features thereof will be made clear from the following description and accompanying drawing of one good embodiment of the invention.

In the drawing:—

Fig. 1 is a perspective view showing a portion of a pile carpet or rug having the label of the present invention applied thereto;

Fig. 2 is a section on the line 2—2 of Fig. 1.

The floor covering is composed of a woven

backing fabric 1 to which are connected the pile forming yarns 2 which project upwardly from the woven backing fabric to form a pile surface area which may be either plain or figured.

In the present instance of the invention the end portion of the floor covering is provided with a fringe 3, the heading 4 of which may be secured to the floor covering by suitable means such as the stitches 5. The side edge 60 of the floor covering may have the usual selvage which is shown in the present instance as overstitched as at 6, although it will be understood that the over-stitching may not be necessary and that the selvage edge of 65 the floor covering may terminate adjacent the edge of the pile forming surface.

It has been found in practice that an identifying label may be conveniently connected to the floor covering so that the data bearing 70 portion may extend over or above the pile surface with the result that where a large number of floor coverings, such as carpets or rugs are displayed in a pile, it is only necessary to throw back a corner portion of each 75 as a progressive inspection of the underlying carpets or rugs proceeds.

In the present instance of the invention the data bearing portion of the label extends diagonally across and above the pile surface 80 at the corner of the carpet or rug, as indicated in Fig. 1, and one end portion of the label is shown as secured to the floor covering at 7, while the opposite end of the label is turned about the side edge of the carpet or rug 85 and secured to the under surface thereof by stitching, as at 8 and 9, so that the data bearing portion 10 of the label extends between the end portions of the label above and over a portion of the pile area without injury 90 thereto.

The end portion 7 of the label may be turned under as at 11 and secured to an end portion of the floor covering or the woven backing fabric by a series of fastenings 12 95 which may be of any usual character and as shown are constituted as stitching. Where the end 7 is secured to the floor covering, as indicated, the bend of the label at the end 7 100 will be turned upwardly to present the data

bearing portion 10 of the label above the pile area.

5 The label is formed of flexible material, such for instance as a strip of ribbon-like textile material and the data, such for instance as "best quality", as indicated at 13, may be displayed upon the data bearing portion of the label either by printing, stamping, or by weaving the data information into the material of the label.

10 The end of the label opposite the end 7 is turned about the side edge of the floor covering, as indicated at 14, to carry the terminal end portion of the label beneath the woven backing fabric where it may be secured as hereinbefore stated by suitable stitching or other fastenings.

15 It may sometimes be desirable to have a permanent portion of the label secured to the backing fabric, in which case the portion 20 15 of the label may be secured permanently to the backing and a line of cleavage 16 be provided so that upon removal of the label when the carpet or rug has been sold by cutting or 25 parting the same on the line 16, the portion 15 of the label will remain as a permanent mark on the back of the carpet or rug.

20 From the construction described it will be apparent that the applicant has provided a 30 marker or label for floor coverings shown as comprising a woven backing fabric having secured thereto the upstanding pile forming yarns and that the data bearing portion of the label extends diagonally across the corner 35 of the carpet or rug where it is readily displayed whether the carpets or rugs be exhibited singly or in stacks. As a result of this construction the pile surface of the floor covering is not in any way injured by the 40 label or its attaching means, and the portion of the label that extends across the pile surface is not attached to the pile.

What is claimed is:—

45 1. The combination of a floor covering comprising a woven backing fabric having pile forming yarns secured thereto to form a pile surface area, and a label formed of flexible material having one end secured to the floor covering at the end of the floor covering and the other end secured to the floor covering adjacent a side edge thereof, so that the part 50 of the label between the secured ends thereof shall extend above and overlie a portion of the pile surface area.

55 2. The combination of a floor covering formed of a woven backing fabric having pile forming yarns connected therewith to form a pile surface area, and a label formed of flexible textile material having end portions 60 one of which is secured to the woven backing fabric in contacting relation with a side edge of the floor covering and the other of which is secured to the end of the floor covering with the part of the label between the secured end portions extending in a diagonal direc- 65

tion over and above a portion of the pile surface area.

3. The combination of a floor covering formed of woven textile material, a label formed of a strip of flexible textile material, 70 and means for connecting one end portion of the label to the end of the floor covering and the other end portion of the label to the floor covering adjacent a side edge thereof that the portion of the label between the end 75 portions shall extend diagonally over the upper surface of the floor covering.

4. The combination of a floor covering having a pile surface, a flexible corner label for the floor covering formed of a strip of ribbon-like textile material extending diagonally over the pile forming area at the corner of the floor covering, and means for securing one end of the corner label to the end of the floor covering and the other end to the floor covering in contacting relation with a side edge thereof. 80 85

5. The combination of a floor covering having a pile surface, a corner label for the floor covering formed of flexible textile material 90 extending diagonally over the pile area and forming a data bearing portion at a corner of the floor covering and having a part folded around a side edge of the floor covering and secured to the back thereof to provide 95 a permanent data bearing portion, and means for securing the other end of the corner label to the floor covering.

6. The combination of a floor covering, a label formed of flexible material, and means 100 for so securing one end portion of the label to the end of the floor covering and the other end portion of the label to the floor covering adjacent a side edge thereof at a distance from said end of the floor covering that the portion of the label between the secured end portions thereof shall extend diagonally over a 105 surface of the floor covering in non-attached relation to said surface.

In testimony whereof, I have signed my 110 name to this specification.

ELLIOTT I. PETERSEN.
